M. L. PARRET.
MOVING PICTURE MACHINE SHUTTER.
APPLICATION FILED SEPT. 14, 1920.

1,386,198.

Patented Aug. 2, 1921.

UNITED STATES PATENT OFFICE.

MILTON L. PARRET, OF MARSHALLTOWN, IOWA.

MOVING-PICTURE-MACHINE SHUTTER.

1,386,198.

Specification of Letters Patent. Patented Aug. 2, 1921.

Application filed September 14, 1920. Serial No. 410,250.

To all whom it may concern:

Be it known that I, MILTON L. PARRET, a citizen of the United States, and a resident of Marshalltown, in the county of Marshall and State of Iowa, have invented a certain new and useful Moving-Picture-Machine Shutter, of which the following is a specification.

The object of my invention is to provide a shutter device sometimes called a light breaker for moving picture machines of very simple and inexpensive construction.

More particularly it is my object to provide such a device having a plurality of series of spaced members, adapted to be intermittently moved into the path of travel of the light through the machine in any manner, as the members of each series travel in different directions, but substantially 20 simultaneously, through said path.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 shows a vertical, sectional view 30 through a moving picture machine, equipped with a light breaker embodying my invention.

Fig. 2 shows a detail, sectional view taken on the line 2—2 of Fig. 1.

Fig. 3 shows a detail, sectional view taken on the line 3—3 of Fig. 2.

Figs. 4 and 5 show diagrammatic views illustrating the light breaker in different positions of its movement with relation to the 40 path of light; and

Fig. 6 is a preferred form of my device showing the spaced members arranged in groups, the members of which are placed obliquely with relation to the axis of the 45 device.

In the accompanying drawings I have used the reference numeral 10 to indicate generally the frame of a moving picture machine, having the fire shutter 11 adjacent to the light aperture 12 and having the lens 13. The main power shaft is indicated by the reference numeral 14. A gear 15 meshes with a gear 16 on the shaft 17.

On the shaft 17 which is the light breaker 55 shaft is a supporting member, such as a disk

18. Projecting laterally from the disk 18 are two series of wires 19. The wires of each series are arranged in the arc of a circle, having its center at the center of the shaft 17.

It will be seen that the light breaker thus has substantially the form of a cylinder, as here shown, although it may be made in a great variety of forms.

It should be mentioned that the wires 19 65 are preferably of such thickness in the direction of their path of travel through the light and are so located with reference to each other in the series that the distance between the wires is substantially less than 70 such thickness of the wires.

It may be mentioned also that the distance between the series is less than the length of the series circumferentially of said cylinder.

In the practical use of my improved light 75 breaker, the light breaker shaft 17 is rotated at such a speed that it travels one and one-half revolutions, during the time that one picture is being thrown on the screen and the next picture is being moved to position to be thrown on the machine.

In Fig. 5, I have shown the position of the light breaker just as the picture stops and is ready to be thrown on the screen.

The light breaker moves substantially one- 85 and one-fourth revolutions from its position shown in Fig. 5 and thereupon the intermittent movement device operates during the next quarter revolution of the light breaker.

During the time of the movement of the 90 film, the series of wires or the like 19 are both interposed in the path of light.

Fig. 5 shows the position of such series just at the finish of the movement of the film, while Fig. 4 shows the position at about 95 the time the film has half completed its movement.

It may be mentioned that my invention may be constructed in a variety of forms. By the use of the term "wires" in my claim, 100 I intend any form of opaque members, whereby the result can be obtained.

It may be mentioned also that this series may be mounted on different supports, if desired.

Among the important features, which I desire to embody in my invention is the arrangement of the wires or the like in at least two different series, and the bringing of the series intermittently into the path of light 110

in such manner that the series move simultaneously, and yet move across the path of light in different directions.

The open spaces 20 between the two series 5 19 may be broken by a small number of wires or the like 21.

In Fig 6 I have shown the series of wires arranged obliquely to the axis of the cylinder. When the series of wires or spaced 10 members, as shown in Fig. 6 are in the path of light the light will be spread out to a much greater degree.

It will be understood that the light breaker may be mounted forwardly of the lens 13 as 15 desired. In my experiments I have found that the light breaker will work as effectively in either position.

Some changes may be made in the construction and arrangement of the parts of

my device, and it is my intention to cover 20 by my claim, any modified forms of structure or use of mechanical equivalents, whereby my objects may be attained, and within the scope of my claim.

I claim as my invention:

The combination with a moving picture projection machine, a light breaker or shutter device comprising a cylindrical shaped member having a pair of series of obliquely arranged members adapted to be intermittently moved into the path of light for partially shutting off the light during the movement of the film from one picture to the other for substantially eliminating the flicker.

Des Moines, Iowa, September 3, 1920.

MILTON L. PARRET.
